UNITED STATES PATENT OFFICE.

WILLIAM B. FULTON, OF MIDDLETOWN, OHIO.

DRIER-HEATING SYSTEM.

1,380,373.

Specification of Letters Patent.

Patented June 7, 1921.

Application filed October 1, 1919. Serial No. 327,783.

To all whom it may concern:

Be it known that I, WILLIAM B. FULTON, a citizen of the United States, residing at Middletown, Butler county, Ohio, have invented certain new and useful Improvements in Drier-Heating Systems, of which the following is a specification.

This invention pertains to improvements in systems for heating driers. It is especially applicable to rotary drying cylinders employed in drying the web in the process of paper making, and I have chosen such a paper machine drier for illustration.

The invention will be readily understood from the following description taken in connection with the accompanying drawing in which:—

Figure 1 is a diametrical section of a part of an exemplifying cylindrical paper drier: 20 and

Fig. 2 an end elevation of two series of such driers shown in connection with a system exemplifying my present invention.

In the drawing, referring to Fig. 1:— 25 1, indicates the shell of an ordinary rotary paper machine drier:

2, the steam inlet thereto: and

3, the water outlet therefrom.

In the ordinary construction, exemplified 30 in Fig. 1, the heating steam enters and the water of condensation leaves at the same end of the drier, which is quite usual, and my present improvements, when employed in connection with paper machine driers,

35 contemplate either that the steam may enter at one end of the drier and the water of condensation leave at its other end, or that the entry of steam and the departure of condensation water may take place at the 40 same end of the drier.

Proceeding with the drawing:—

4, indicates a secondary group of the driers, the group being illustrated as containing two driers:

45 5, a supply-pipe for conveying comparatively high-pressure steam to these driers:

6, a discharge-pipe for conveying steam at lowered pressure, as well as the water of condensation from these driers:

50 7, a receiver:

8, a pipe placing the upper portion of the receiver in connection with the discharge 6 of the secondary driers:

55 9, a primary group of driers, the group being illustrated as containing two driers:

10, a supply-pipe placing the upper part of the receiver in communication with the primary driers 9:

11, a discharge-pipe connected with the primary driers 9 for conveying from them 60 their contents consisting of vapor at reduced or zero pressure, as well as air and the water of condensation:

12, a suction device, illustrated as a pump:

13, a pipe placing the suction device in 65 connection with the discharge pipe 11 of the primary driers:

14, a condenser, which may be of either the surface or jet type, disposed in pipe 13:

15, steam traps, of any usual character, 70 disposed in the individual discharge pipes of the primary driers 9:

15^a by-pass pipes around the steam traps 15:

15^b, a valve in each of these by-pass pipes;

16, an assumed water-level in the re- 75 ceiver:

17, a float-valve disposed within and controlled by the level of water in the receiver and adapted to be opened by the rising of the float:

18, a pipe placing the float valve 17 in communication with the suction device 12:

19, a pipe placing the upper portion of the receiver in connection with the suction device 12:

20, a check-valve in pipe 19 opening away 80 from the receiver:

21, a stop-valve in pipe 19:

22, the stem of this stop-valve:

23, a diaphragm connected with this stem:

24, a pipe placing a chamber above the diaphragm in communication with the upper portion of the receiver:

25, a weighted lever connected with the stem of the stop-valve and tending to open 95 the valve: and

26, an arrow indicating the direction of motion of the paper being dried, the paper passing first over the primary driers and then over the secondary driers.

Let it be assumed that the secondary driers 4 are supplied with steam at comparatively high pressure. This steam heats the driers 4 and, by parting with heat, becomes reduced in pressure and, along with the water condensed in these driers, goes through pipe 8 to the receiver 7, water of condensation, entrained in the steam discharged from these driers, falling to the 105

base of the receiver where its accumulation will eventually cause it to stand at the level 16.

The steam at reduced pressure, leaves the receiver through pipe 10 and goes to the primary driers 9 and effects the heating of those driers, but to a lower temperature than secondary driers 4. The steam in the primary driers 9 parts with heat and becomes reduced in pressure and these driers discharge through pipes 11 and 13, the discharge being withdrawn by the suction device 12, the discharge consisting of the water of condensation and air, and possibly some steam, the suction device producing, possibly, a partial vacuum in the primary driers. The steam traps 15 open, as usual, in the presence of excessive water and form partial seals between the primary driers and the suction device and prevent the overwhelming of the suction device with steam from the driers. The condenser 14 serves in condensing the discharge from the primary driers, when those driers discharge steam, the condenser delivering its water of condensation to the suction device. The receiver 7 is provided with a baffle 7^a, as shown between its inlet from pipe 8 and its outlet to pipe 10, this baffle preventing the direct flow of steam between the two pipes and causing the water entrained in the discharge from pipe 8 to seek the lower part of the receiver. The water in the base of the receiver stands normally at the level 16, and when the level of water rises then the float opens valve 17 and the suction device withdraws water from the receiver.

Diaphragm 23 has its upper surface subjected to the pressure of the steam in the receiver and holds valve 21 normally closed, against the resistance of the action of weight 25, pipe 19 being without office under such conditions. If, however, the pressure in primary driers 9 falls or is lost entirely, as a result of their own action, then the receiver may possibly cease to withdraw the water and air from the secondary driers. In such case the lowering of the pressure in the receiver relieves the pressure over diaphragm 23, whereupon valve 21 opens and permits the suction device 12 to draw directly upon the receiver through pipe 19, the same as if the primary driers were not in existence.

The suction device 12, in acting through pipes 13 and 19, finds, in the weight of the valve proper, in check-valve 20, a slight differential resistance whereby the superior suction is exerted on pipe 13 and the primary driers 9.

By-passes 15^a enable the suction device to be always acting on the primary driers 9 so as to remove steam, water of condensation, and air from those driers even while the traps are not indicating that water is

to be removed from the driers, and the valves 15^b are to be so regulated that the suction device will always draw sufficiently on the primary driers.

I have referred to the group of driers 9 as primary and the group of driers 4 as secondary, in view of the fact that in the drying of paper, for instance, it is usual to first subject the paper to drying at the lower drying heat and subsequently subject it to drying at the higher drying heat, the paper in such case passing the driers in the direction of arrow 26, the paper being thus subjected to its primary drying action at the driers 9 and to subsequent drying action at the secondary driers 4.

While I have illustrated my system as comprising but two groups of driers, each group containing two driers, each group may contain any desired and proper number of driers, and there may be as many groups as desired, a receiver and valve 21, with their accessories, being disposed between each two groups.

It is to be understood that, even in the absence of the traps 15, the valves 15^b serve in introducing a restriction between the driers 9 and the suction device, such restriction serving to prevent the overwhelming of the suction device by steam from the driers, while still permitting the suction device to withdraw from the driers the water of condensation and air in quantities as limited by the restriction introduced in the pipes between the driers and the suction device.

I claim:

1. A drier system comprising, a group of secondary driers, a pipe for supplying steam thereto, a receiver, a pipe placing the receiver in communication with said secondary driers, a group of primary driers, a pipe placing the receiver in communication with the primary driers, a suction device, a suction-pipe placing the suction device in communication with the primary driers, a pipe placing the suction device in communication with the base of the receiver, and a float valve within the receiver on said last mentioned pipe and having its float adapted to open the valve by the rise of accumulated water in the receiver, combined substantially as set forth.

2. A drier system comprising, a group of secondary driers, a pipe for supplying steam thereto, a receiver, a pipe placing the receiver in communication with said secondary driers, a group of primary driers, a pipe placing the receiver in communication with the primary, a suction device, a suction-pipe placing the suction device in communication with the primary driers, a pipe placing the suction device in communication with the base of the receiver, a valve in said last-mentioned pipe arranged to

open by the rise of the level of water in the receiver, and steam traps disposed between the primary driers and the suction device, combined substantially as set forth.

- 5 3. A drier system comprising, a group of secondary driers, a pipe for supplying steam thereto, a receiver, a pipe placing the receiver in communication with said secondary driers, a group of primary driers, a pipe placing the receiver in communication with the primary driers, a suction device, a suction-pipe placing the suction device in communication with the primary driers, a pipe placing the suction device in communication with the base of the receiver, and a condenser disposed in the discharge pipe between the primary driers and the suction device, combined substantially as set forth.

- 10 4. A drier system comprising, a group of secondary driers, a pipe for supplying steam thereto, a receiver, a pipe placing the receiver in communication with said secondary driers, a group of primary driers, a pipe placing the receiver in communication with the primary driers, a suction device, a suction-pipe placing the suction device in communication with the base of the receiver, a valve 15 in said last-mentioned pipe arranged to open by the rise of the level of water in the receiver, steam traps disposed between the primary driers and the suction device, bypass pipes at such steam traps, and regulating valves in such bypass pipes, combined substantially as set forth.

- 20 5. A drier system comprising, a group of secondary driers, a pipe for supplying steam thereto, a receiver, a pipe placing the receiver in communication with said secondary driers, a group of primary driers, a pipe placing the receiver in communication with the primary driers, a suction device, a suction-pipe placing the suction-device in communication with the primary driers, a pipe placing the suction device in communication with the base of the receiver, a float-valve 25 in said last-mentioned pipe and arranged to be opened by the rising of the level of the accumulated water in the receiver, a pipe placing the suction-device in communication with the upper portion of the receiver, a normally closed valve in such pipe, a diaphragm connected with the stem of such 30 valve and having one of its surfaces subjected to the pressure in the receiver, and a weight adapted to open such valve when the pressure over the diaphragm is reduced, combined substantially as set forth.

- 35 6. A drier system comprising, a group of secondary driers, a pipe for supplying steam thereto, a receiver, a pipe placing the receiver in communication with said secondary driers, a group of primary driers, a pipe

placing the receiver in communication with the primary driers, a suction device, a suction-pipe placing the suction-device in communication with the primary driers, a pipe placing the suction device in communication with the base of the receiver, a float-valve in said last-mentioned pipe and arranged to be opened by the rising of the level of the accumulated water in the receiver, a pipe placing the suction-device in communication with the upper portion of the receiver, a normally closed valve in such pipe, a diaphragm connected with the stem of such valve and having one of its surfaces subjected to the pressure in the receiver, a means adapted to open such valve when the pressure of the diaphragm is reduced, and a check-valve in said pipe placing the suction device in communication with the upper part of the receiver and adapted to furnish a resistance in said pipe, combined substantially as set forth.

7. A drier system comprising, a group of driers, a pipe for supplying steam thereto, a receiver, a pipe placing the receiver in communication with said secondary driers, a group of primary driers, a pipe placing the receiver in communication with the primary driers, a suction device, a pipe placing the suction device in communication with the base of the receiver, a valve in said last-mentioned pipe arranged to open by the rise of the level of water in the receiver, pipes placing the primary driers in communication with the suction device, and restriction devices in said last mentioned pipes to limit the flow from the driers to the suction device, combined substantially as set forth.

8. A drier system comprising primary and secondary groups of driers, means for supplying steam to said secondary group, means for withdrawing steam, air and water of condensation from said secondary group, means for separating the water from said steam and air, means for conducting the separated steam and air to said primary group of driers, a common suction device for exhausting said primary group of driers and for withdrawing water from said separating means and means for connecting said suction device with the steam space in said separating means when the pressure in said primary group of driers falls to a predetermined value.

9. A drier system comprising primary and secondary groups of driers, means for supplying steam to said secondary group, means for withdrawing steam, air and water of condensation from said secondary group, means for separating the water from said steam and air, means for conducting the separated steam and air to said primary group of driers, and a common suction device for

exhausting said primary group of driers and for withdrawing water from said separating means.

10. A drier system comprising primary and secondary groups of driers, means for supplying steam to said secondary group, means for withdrawing steam, air and water of condensation from said secondary group, means for removing the water from said steam and air, means for conducting the separated steam and air to said primary group of driers, means for withdrawing steam, air and water of condensation from said primary group, and means intermediate said primary group and said withdrawing means for condensing the steam withdrawn from said primary group.

means for supplying steam to said drier, means for withdrawing steam and water of condensation from said drier comprising a pipe and a suction device secured to said pipe, there being a restriction in said pipe and a steam trap connected with said pipe around said restriction.

12. A drier system comprising a drier, means for supplying steam to said drier, means for removing water of condensation from said drier comprising a steam trap and a suction device for removing steam from said drier, and causing the water of condensation to flow into said steam trap.
